United States Patent Office

Des. 203,408
Patented Jan. 4, 1966

203,408

KEY BLANK

Alois Crepinsek, San Jose, Calif., assignor to 777 Lock
and Engineering Corp., San Jose, Calif.

Filed Nov. 20, 1964, Ser. No. 82,706

Term of patent 7 years

(Cl. D50—4)

Fig. 1

Fig. 3

Fig. 4

Fig. 5

FIGURE 1 is a front elevational view of a key blank showing my new design, the back view being a mirror image of the front view.

FIGURE 2 is a top plan view thereof.

FIGURE 3 is a side elevational view thereof, the reverse side being a mirror image thereof.

FIGURE 4 is a bottom view thereof.

FIGURE 5 is a perspective view of the key blank.

The dominant features of my design reside in the portions shown in full lines.

I claim:

The ornamental design for a key blank, as shown and described.
